UNITED STATES PATENT OFFICE.

FELIX EBERHART, OF NEWARK, NEW JERSEY, ASSIGNOR TO AMERICAN CAN COMPANY, OF NEW YORK, N. Y., A CORPORATION OF NEW JERSEY.

DESIGN FOR A SIFTER-CAN.

47,663.

Specification for Design.

Patented Aug. 3, 1915.

Application filed May 21, 1915. Serial No. 29,671. Term of patent 7 years.

To all whom it may concern:

Be it known that I, FELIX EBERHART, a citizen of the United States, residing at Newark, Essex county, and State of New Jersey, have invented a new, original, and ornamental Design for a Sifter-Can, of which the following is a specification, reference being had to the accompanying drawing, forming a part thereof.

On the drawing: Figure 1 is a top plan

view of the sifter can illustrating my new design; Fig. 2 is a side elevation of the sifter can.

I claim:—

The new, original and ornamental design for a sifter can, as shown.

FELIX EBERHART.

Witnesses:

D. F. MENNIS,

W. D. FOSTER.
